CLAIM

The ornamental design for a toggle for a self-powered wireless switch, as shown and described.

DESCRIPTION

FIG. 1 is a side perspective view of a first embodiment of a toggle for a self-powered wireless switch;

FIG. 2 is a side view thereof;

FIG. 3 is an opposing side view thereof;

FIG. 4 is an end view thereof;

FIG. 5 is an opposing end view thereof;

FIG. 6 is a top view thereof;

FIG. 7 is a bottom view thereof;

FIG. 8 is a top perspective view of a second embodiment of a toggle for a self-powered wireless switch;

FIG. 9 is a side view thereof;

FIG. 10 is an opposing side view thereof;

FIG. 11 is an end view thereof;

FIG. 12 is an opposing end view thereof;

FIG. 13 is a top view thereof; and,

FIG. 14 is a bottom view thereof.

The broken lines in the drawings depict portions of the switch that form no part of the claimed design.
